UNITED STATES PATENT OFFICE

FELIX C. MONTUORI, OF WASHINGTON, DISTRICT OF COLUMBIA, ASSIGNOR TO BAKER & COMPANY, INC., A CORPORATION OF NEW JERSEY

DENTURE RETAINING DEVICE

Application filed March 18, 1930. Serial No. 436,653.

The objects of this invention are to secure denture retaining devices such as lingual and palatal bars and clasps that are used in partial dentures which can be readily shaped to the contour of the patient's mouth and yet shall be stiffly rigid as is necessary in use to hold the saddles in proper relative position; to secure a bar of such construction that it is at first yielding for the purpose of fitting it to the patient's mouth and afterward is made rigid as desired; to secure such a bar having a soft pliable base portion which can be fitted and which base portion is adapted to subsequently receive stiff solder or similar material to complete the bar; to provide in a denture retaining device a thin sheet metal portion which will readily take the shape of the patient's mouth, said sheet metal portion having at one side wire or the like which is pliable so as to be shaped as desired and at the same time retain such shape for itself and the sheet metal, whereby a body portion is secured which may be filled with or have applied thereto stiff solder to complete the bar; to thus enable bars to be readily and accurately fitted before they are stiff and yet when finished to be rigid to resist bending and hold the saddles fixedly in position, and to secure other advantages and results as will be brought out in the following description.

Referring to the accompanying drawings, in which like characters of reference indicate the same parts throughout the several views,

Figure 1 shows in a plane a piece of light sheet metal such as is used for the body of a lingual bar embodying my invention;

Figure 2 shows the same with a rim formed on one side thereof by spot soldering a piece of wire thereto, thus forming the body portion of my improved bar;

Figure 3 shows said body portion with wax applied thereto to facilitate bending and shaping it to the contour of the model;

Figure 4 shows said body portion bent or shaped to the contour of a model, and part of the wax removed;

Figure 5 shows stiff solder or the like applied to the body portion of the bar so as to complete the bar, and

Figure 6 is a cross-section on line 6—6, Fig. 5.

In the specific embodiment of the invention set forth in said drawings, 1 indicates a strip of thin malleable metal such as palladium or the like, which is adapted to be bent and shaped to the mouth of the patient or a model thereof which is commonly used for the purpose. This strip 1 is, for a lingual bar, preferably somewhat arcuate in its plane, as shown in Figures 1 and 2, so that it lies horizontally in the mouth when shaped, and the ends of the strip 1 are preferably apertured as shown at 2, 2 to provide in the completed bar openings for the material of the saddles to enter and thus secure a better attachment.

To one side of the said strip 1, while it is still in plane form, is soldered a wire 3 extending clear around the strip, near its peripheral edge, with its ends substantially meeting at a suitable point, as at 4, said wire lying outside the apertures 2, 2. This wire 3 is of such composition that when applied to the strip 1, as shown in Figure 2, the combined strip and wire can be readily shaped to the patient's mouth or model thereof, and when so shaped will retain such shape or form. The body part of my improved lingual bar, consisting of the strip 1 and wire 3, forming a rim, is preferably filled with wax 5, as shown in Figures 3 and 4, which is toughly yielding and helps distribute and equalize the pressure of the operator's fingers in contouring the body portion to the model. Said body portion is shown in Figure 4 as shaped to fit a particular patient, and when it has been so shaped, the wax 5, if it has been used, is melted or burned off, as by a blow torch, and the space or recess enclosed by the rim wire 3 is filled at the inner or concave side of the body part with stiff solder or equivalent material 6 which will give said inner or convex side of the lingual bar a rounded or approximately semi-cylindrical surface and sufficient body or thickness to afford the necessary rigidity. This completes the bar which then appears as shown in Figure 5, openings 2, 2 being still left in the ends of the arms of the bar, although the stiff solder or the like may extend around the same. The cross-

section 6—6, Fig. 5, shows the solder 6 filling the space between the wire 3 and the inner side of the strip 1, and the solder 6 being continuous with the wire 3 at the point 4. The solder 6 is of such composition that it will not melt when the wax 5 is melted, and will not melt when the bar is heated by a blow torch.

section of the bar appears as shown in Figure 6, the wire 3 being embedded in the stiff solder 6. The stiff solder or the like 6 is given a smoothly rounded and finished surface merging into the exposed side of the sheet metal strip 1, and thus a bar is provided which can be utilized for a partial denture in a manner similar to bars previously in use.

10. While I have shown my invention embodied in a lingual bar or bar for a lower denture, it will be obvious that the invention can be similarly embodied in a palatal bar or bar for an upper denture, or other denture retaining devices.

11. It will be seen that my improved bar is very readily and conveniently made, and furthermore can be very accurately fitted, since the fitting is all done while the body part of the bar is soft and yielding, pliable or malleable, so that there is no great resistance to the shaping of it to the model of the patient's mouth. Such body part can be very nicely and accurately shaped, and such shaping is not in any way disturbed by the application of the stiff solder or the like to the inner or concave surface of the body part. Such stiff solder or the like is of such a nature that it gives to the completed lingual bar the stiffness and rigidity desired and yet such stiffness and rigidity are secured wholly subsequent to the shaping or fitting of the soft and yielding body part.

12. In marketing my invention, a body part, consisting of the preferably thin sheet metal strip with the rim or wire mounted thereon, and filled in with wax compound, is sold ready for shaping, and with it the proper amount of stiff solder to be applied by the user after the body part is shaped or fitted. Obviously, if desired, the wax can be omitted, and various other modifications may be made in carrying out my invention, by those skilled in the art, without departing from the spirit and scope of my invention, and therefore I do not desire to be understood as limiting myself, except as required by the following claims, when construed in the light of the prior art.

13. Having thus described the invention, what I claim is:

1. The method of making a denture retaining device, which consists in shaping or fitting a pliable body part to a model, and applying a reinforcing stiffening to the shaped body part.

2. The method of making a denture retaining device, which consists in shaping or fitting a pliable body part to a model, and soldering a reinforcing stiffening to the shaped body part.

3. The method of making a denture retaining device, which consists in shaping or fitting a pliable body part to a model, and ap-

plying stiff solder or the like to the shaped body part.

4. The method of making a denture retaining device, which consists in shaping or fitting a pliable sheet metal body part to a model, and applying stiff solder or the like to the shaped body part.

5. The method of making a denture retaining device, which consists in shaping or fitting a pliable sheet metal body part to a model, and applying stiff solder or the like to the inner concave side of the shaped body part.

6. The method of making a denture retaining device, which consists in shaping or fitting to a model a pliable sheet metal body part having a raised rim, and applying stiff solder or the like to the side of the shaped body part having said rim.

7. The method of making a denture retaining device, which consists in applying wax to a pliable sheet metal body part, shaping or fitting to a mold said body part with the wax thereon, removing said wax compound, and applying stiff solder or the like to the shaped body part.

8. A denture retaining device comprising a pliable body part to be shaped or fitted to a model, and a stiffening for said body part secured thereto.

9. A denture retaining device comprising a pliable body part which has been shaped or fitted on a model of a mouth, and a stiffening which has been applied to said body part after said shaping or fitting of it.

10. A denture retaining device comprising a pliable body part to be shaped or fitted to a model, and a stiffening of stiff solder secured to said body part.

11. A denture retaining device comprising a pliable sheet metal body part, and a stiffening for said body part soldered thereto after shaping of the body part to a model.

12. A denture retaining device comprising a pliable body part having a raised edge, and a stiffening secured to the side of said body part having said raised edge.

13. As an article of manufacture, a body part for a denture retaining device comprising a strip of pliable sheet metal to be shaped or fitted to a model and having an elongated recess in one side thereof to receive stiffening and reinforcing material after said body part has been shaped.
